SHEET METAL WORKING MACHINE

Filed Sept. 25, 1928

UNITED STATES PATENT OFFICE

PAUL R. HAHNEMANN, OF BUFFALO, NEW YORK, ASSIGNOR TO NIAGARA MACHINE AND TOOL WORKS, OF BUFFALO, NEW YORK, A CORPORATION OF NEW YORK

SHEET METAL WORKING MACHINE

Application filed September 25, 1928. Serial No. 308,183.

This invention relates to a sheet metal working machine for beading, edging, turning and wiring sheet metal and has the object to produce a machine of simple, durable, efficient and inexpensive construction in which the housing is made in one piece, the horn is made separate from the housing and the gears for connecting the shafts are arranged within the housing and are inserted 10 and removed through an opening in the rear end of the same.

In the accompanying drawings:

Figure 1 is a side elevation of a metal working machine embodying my invention. 15 Figure 2 is a vertical longitudinal section of the same.

Figures 3 and 4 are vertical transverse sections taken on the correspondingly numbered lines in Fig. 2.

20 In the following description similar characters of reference indicate like parts in the several figures of the drawings:

The main frame of this machine is constructed in one integral body preferably by 25 casting the same of metal and comprises a rear hollow part 10 which constitutes a housing or casing for enclosing some of the working parts of the machine, and an upper hollow overhanging supporting arm 11 which 30 projects forwardly from the upper part of the housing 10.

This frame may be mounted in any suitable manner but preferably by means of a stem 12 projecting downwardly from the lower end 35 of the housing 10 and adapted to engage a standard in the usual and well known manner in which machines of this character are mounted.

The housing is provided in its front wall 40 13 with a horizontal and longitudinally extending opening 14, and between its front and rear ends the housing is provided with a transverse bracket, web or partition 15 which has a horizontal longitudinal opening 16, 45 this opening and the opening 14 in the front wall being both of cylindrical form and axially in line with each other.

The rear end or wall 17 of the housing is 50 provided with an opening 18 which normally is preferably closed by means of a cover 19

detachably secured thereto by means of screws 20 or other suitable fastening.

The numeral 21 represents a horizontal longitudinal horn of cylindrical form which is arranged below the arm of the frame and 55 inserted with its rear part through the openings 14 and 16 in the front wall and bracket of the housing and is securely held therein both against turning and longitudinal movement by means of a set screw 22 arranged in 60 the side of the housing and engaging with the adjacent rear part of the horn 21, as shown in Figs. 1 and 3.

At its front and rear ends this horn is provided with internal front and rear bearings 65 23, 24, in which the front and rear parts of a lower horizontal longitudinal shaft 25 are journaled.

At its front end this lower shaft is provided with a forming roll 26 which may have 70 its periphery made of any desired form in order to produce the required beading, edging, turning or wiring on the sheet of metal 27 by engaging the under or inner side of the latter. When this sheet is presented to the machine its advancing edge abuts against a gage 28 which is adjustably secured to the horn by means of a clamping screw 29 so as to adapt the machine for working on sheets 75 of metal at different places thereon.

At its rear end the lower shaft is provided 80 with a gear wheel 30 which abuts against the rear end of the horn, said lower shaft being provided near its front end with a rearwardly facing shoulder 31 which engages with the front end of the horn, whereby the shoulder 31 and the gear wheel 30 serve to hold the lower shaft against longitudinal movement.

Above the lower shaft is arranged a horizontal longitudinal upper shaft 32 which has 85 its rear part extending through the upper part of the housing and its front part extending through the hollow under side of the frame arm 11 and the rear part of this upper shaft also extending through an opening 33 in the rear cover 19. At its front end the upper shaft is provided with an upper forming roll 34 which has its periphery made in conformity with that of the lower roll 26 so 90 that upon engaging with the upper or outer 95 100 cover 19 the upper roll 34 will be held in position by the shoulder 31.

side of the sheet of metal 27 in cooperation with the lower roll 26 this sheet will be provided with the desired beading, edging, turning or wiring in a well known manner by turning the shafts so that the opposing surfaces of the rolls move in the same direction and move the sheet of metal between them as the forming operation of the latter progresses.

10 Adjacent to its front and rear ends the upper shaft is journaled in an upper front bearing 35 and an upper rear bearing 36. The rear bearing 36 is pivotally mounted on the 15 frame so as to permit the upper shaft to swing vertically for varying the distance between the rolls to suit the character of the work and the thickness of the sheet which is being operated upon. This pivotal connection between the rear bearing 36 and the frame is preferably effected by means of two pivot screws or trunnions 37 working in threaded openings on opposite sides of the upper part of the housing and provided at their inner opposing ends with cones 38 which engage with pivot seats 39 on opposite sides of the rear bearing 36, each of said pivot screws being held in place after adjustment by means of a clamping nut 40 mounted thereon and engaging with the outer side of the housing, as 20 shown in Figs. 1 and 2.

25 The upper front bearing 35 is capable of moving vertically on the front part of the frame arm and is guided during this movement by providing its opposite side with vertical guide faces 41 engaging with corresponding vertical guide faces 42 on the opposing internal parts at the front end of the frame arm 11, as shown in Figs. 2 and 4.

40 Downward movement of the upper front bearing 35 is produced by means of a vertical depressing screw 43 working in a threaded opening in the upper front part of the frame arm and engaging its lower end with the top of the upper bearing 35, this screw being preferably provided with a crank 44 at its upper end for convenience in turning the same. Upward movement of the upper front bearing 35 is effected by a yielding lifting device, which in the preferred construction consists of an upright lifting rod 45 which passes through an opening 46 in the upper part of the frame arm 11 and is secured to the upper rear part of the bearing 35 by 45 means of a screw joint 47 and is provided at its upper end with a notched head 48 so that the same may be turned by means of a screw driver for attaching the same to or removing the same from its upper bearing.

50 The numeral 49 represents a helical spring surrounding the upper part of the lifting rod 45 within a socket 50 on the frame arm and bearing at its lower end against the bottom of this socket while its upper end bears 55 against the downwardly facing shoulder

which is formed by the head or enlargement 48 on the upper end of the lifting rod.

Upon turning the depressing screw 43 in one direction the front bearing 35 will be lowered and during this time the spring 49 will be compressed, but upon reversing the rotation of the screw 43 so as to permit this bearing 35 to rise, the resilience of the spring 49 will lift this bearing and hold the same in contact with the lower end of the screw 43, thereby permitting raising and lowering of this upper front bearing by merely manipulating the hand crank 44.

60 Rotation of the upper shaft 32 is effected by means of a hand crank 51 applied to the rear end of the same, outside of the housing cover 19. Motion is transmitted from the upper shaft 32 to the lower shaft 25 by means of a gear wheel 52 secured to the rear part of the upper shaft and meshing with the lower gear wheel 30, as shown in Figs. 2 and 3. This upper gear wheel 52 engages with the rear side of the rear bearing 36, so as to prevent forward movement of the upper shaft while rearward movement of the same is prevented by means of a washer 53 interposed between the front side of the bearing 36 and a rearwardly facing shoulder 54 on this shaft, as shown in Fig. 2.

65 The upper and lower gear wheels 52 and 30 are inserted into the rear part of the housing for applying them to the rear ends of the shafts, and these gear wheels are also removed from these shafts and the housing through the opening 18 in the rear end of the housing, it being understood that during such insertion or removal of the gear wheels the rear cover 19 and the crank 51 are detached from the housing and upper shaft.

70 Due to this organization of the frame, the manner of mounting the rear end of the horn thereon, and the means for inserting and removing the gear wheels through an opening in the rear end of the frame, the construction of the machine is materially simplified and its cost is reduced, and in addition thereto the efficiency of the machine is improved, inasmuch as there are less parts to look after or get out of order.

75 By making the frame hollow and in one piece and the horn separate therefrom, the stiffness of the frame is materially increased, the same forms a guard for the gearing, and it is possible to machine the horn more easily and at less cost.

80 The means for effecting the vertical adjustment of the upper front bearing are also advantageous in that the lifting device for this bearing is always in view and readily accessible in case the spring 49 requires removal and this can be effected without dismantling the machine.

85 I claim as my invention:

90 1. A metal working machine comprising a frame having a hollow rear part forming a

housing and an overhanging arm projecting forwardly from the upper part of said housing, the lower part of said housing having a front wall, an intermediate inner transverse bracket and a rear wall provided with an opening; a separate lower horn passing at its rear end through said front wall and bracket and supported thereby; a lower shaft journaled in said horn and provided at its front end with a lower forming roll; an upper shaft passing through the upper part of the housing and under said arm and provided at its front end with an upper forming roll; an upper front bearing which is mounted on the front end of the arm and in which the front part of the upper shaft is journaled; an upper rear bearing which is mounted on the upper part of the housing; and intermeshing gear wheels which are secured to the rear ends, respectively, of the upper and lower shafts and which are insertable and removable through the rear opening of said housing.

2. A metal working machine comprising a frame having a hollow rear part forming a housing and an overhanging arm projecting forwardly from the upper part of said housing, the lower part of said housing having a front wall, an intermediate inner transverse bracket and a rear wall provided with an opening; a separate lower horn passing at its rear end through said front wall and bracket and supported thereby; a lower shaft journaled in said horn and provided at its front end with a lower forming roll; an upper shaft passing through the upper part of the housing and under said arm and provided at its front end with an upper forming roll; an upper front bearing which is mounted on the front end of the arm and in which the front part of the upper shaft is journaled; an upper rear bearing which is mounted in the upper part of the housing; intermeshing gear wheels which are secured to the rear ends, respectively, of the upper and lower shafts and which are insertable and removable through the rear opening of said housing; and a cover for the rear opening of said housing.

3. A metal working machine comprising a frame having a hollow rear part forming a housing and an overhanging arm projecting from the upper part of said housing, the lower part of said housing having spaced apart supports, a separate horn having its rear part mounted on said supports, and shafts mounted on said horn and frame and provided with cooperating forming rolls and driving gearing.

4. A metal working machine comprising a frame having a hollow rear part forming a housing and an overhanging arm projecting forwardly from the upper part of said housing, the lower part of said housing having a front wall, an intermediate inner trans-

verse bracket and a rear wall provided with an opening; a separate lower horn passing at its rear end through said front wall and bracket and supported thereby; a lower shaft journaled in said horn and provided at its front end with a lower forming roll; an upper shaft passing through the upper part of the housing and under said arm and provided at its front end with an upper forming roll; an upper front bearing which is mounted on the front end of the arm and in which the front part of the upper shaft is journaled; an upper rear bearing which is mounted in the upper part of the housing; intermeshing gear wheels which are secured to the rear ends, respectively, of the upper and lower shafts and which are insertable and removable through the rear opening of said housing, said upper front bearing being slidable vertically on said arm and said rear upper bearing being pivoted on said housing to turn about a horizontal transverse axis, a vertical depressing screw working in the upper front part of the arm and engaging the upper side of said upper front bearing; a vertical lifting rod passing through the front part of said arm and connected at its lower end with said upper front bearing and provided at its upper end with a downwardly facing shoulder; and a spring interposed between the upper side of said arm and the shoulder of said rod.

5. A sheet metal working machine comprising a frame having a rear housing provided with a rear inlet and an overhanging arm projecting forwardly from said housing, a separate horn mounted on the lower part of the housing, shafts mounted on said horn, arm and housing and provided with forming rolls, and intermeshing gear wheels mounted on the shafts within the housing and adapted to be passed through said inlet.

In testimony whereof I hereby affix my signature.
